UNITED STATES PATENT OFFICE.

BELLE A. MASON, OF BINGHAMTON, NEW YORK.

TOY.

1,031,135.

Specification of Letters Patent. Patented July 2, 1912.

Application filed March 21, 1912. Serial No. 685,282.

To all whom it may concern:

Be it known that I, BELLE A. MASON, a citizen of the United States, residing at Binghamton, in the county of Broome and State of New York, have invented certain new and useful Improvements in Toys; and I do declare the following to be a full, clear, and exact description of the invention, such as will enable others skilled in the art to which it appertains to make and use the same.

This invention relates to improvements in toys.

One object of the invention is to provide a toy or amusement device which is supposed to be controlled by magical forces whereby fortunes are told.

Another object is to provide a device of this character which will be simple and inexpensive in construction and which will afford an amusing and interesting pastime.

With these and other objects in view, the invention consists of certain novel features of construction, and the combination and arrangement of parts as will be more fully described and claimed.

In the accompanying drawings; Figure 1 is a perspective view of my improved toy illustrating the manner in which the same is used; Fig. 2 is a similar view of the device on a larger scale; Fig. 3 is a vertical cross section thereof.

My improved toy is constructed to simulate a book 1 which is supposed to contain fortunes or life readings and other magical information. The title of the imitation book is "Ten Magic Numbers." In the outer edge of the book is secured in any suitable manner an imitation key 2, said key having a handle which is preferably constructed in the form of laterally projecting blades or wings 3. In the present instance the shank of the key is in the form of a screw adapted to be screwed into the edge of the book. When thus arranged the key will be disposed in position to form a support for the book when the latter is in use for telling the fortune of the person holding the same.

In using the book for the purpose of telling fortunes, the party impersonating the

fortune teller enters the room with a flour-
ish, book in hand and give the following
toast;

Fairies, witches, imp and ghost
Here's to them a merry toast!
What they say we ne'er can doubt
If they turn this book about
In this book the fairies read
Of their life in word and deed.
Witches oft have read this book
Camping near a meadow-brook.
With this key the imps have found
Hidden treasures underground.
While a ghost this book doth turn,
Listen for some truth to learn.

55

60

The first person to have his or her fortune told is seated opposite the fortune teller and places the tip of the first finger under the extreme end of one of the blades or wings of the key handle. At the same time the fortune teller places her finger under the opposite blade or wing of the key. When the fingers are thus engaged with the handle of the key, the book will be supported and balanced between the fortune teller and person having their fortune told. When all is ready the fortune teller repeats slowly the ten magic numbers. 1, 2, 3, 4, 5, 6, 7, 8, 9, 10. At whatever number the book turns the fortune teller repeats in impressive tones the couplet corresponding to the last number repeated, which couplet is supposed to foretell the person's fortune.

Accompanying the book or toy is a key containing a list of ten couplets or fortunes for boys and ten couplets or fortunes for girls. While it will be understood that any suitable couplets or fortunes may be used, the following lists of couplets are preferred. It will be noted that the last word of each of the couplets rhymes with the number of the couplet which number is the last word in the first line of the couplet;

80

85

90

Boys' couplets.

1. If this book doth turn at one,
Your life's work is just begun.
2. If this book doth turn at two,
A true maiden you will woo.
3. If this book doth turn at three,
You will win a high degree.
4. If this book doth turn at four,
Luck awaits you at the door.
5. If this book doth turn at five,
Motor cars you'll own, and drive.
6. If this book doth turn at six,
Oft with titled men you'll mix.

95

100

7. If this book doth turn at seven,
You'll be rich at three times eleven.
  8. If this book doth turn at eight,
You will win a loving mate.
  9. If this book doth turn at nine,
Gold you'll dig from out a mine.
  10. If this book doth turn at ten,
You'll be honored by all men.

Girls' couplets.

- 10 1. If this book doth turn at one,
Nothing you will leave undone.

2. If this book doth turn at two,
Your fond lover will be true.

3. If this book doth turn at three,
Many countries you will see.

4. If this book doth turn at four,
Versed you'll be in ancient lore.

15 5. If this book doth turn at five,
For the best in life you'll strive.

6. If this book doth turn at six,
Soon your wedding-day you'll fix.

7. If this book doth turn at seven,
You'll be blessed with gifts from heaven.

20 8. If this book doth turn at eight,
In mid air you'll meet your fate.

9. If this book doth turn at nine,
Oft with authors you will dine.

25 10. If this book doth turn at ten,
Fame you'll gain with brush and pen.

It will be understood that other games may be played with my improved toy, for instance, the book may be supported in the manner described and the letters of the alphabet repeated until the book turns and the latter repeated at the turning of the book is supposed to be one of the initials of a future friend's name.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is;

1. A toy constructed in the semblance of a book, and a key arranged therein in position to form means whereby the book may be loosely supported and permitted to turn.

2. A toy of the character described comprising an element constructed and arranged to simulate a book having on one of its covers a suitable inscription, a key comprising a threaded shank adapted to be screwed into one edge of the book and having a handle provided with laterally projecting wings adapted to be engaged with the finger tips whereby the book is balanced or loosely supported to permit the same to freely turn.

In testimony whereof I have hereunto set my hand in presence of two subscribing witnesses.

BELLE A. MASON.
